Co., Chicago, Ill., a corporation of Illinois

Application March 25, 1933, Serial No. 662,737

7 Claims. (Cl. 100—50)

My invention relates to an hydraulic press and more particularly to a mechanism of this character which is utilized for the extraction of oils and greases from oil-bearing seeds, animal tissues or cracklings, and other oil-bearing materials whose contents may be substantially removed by the application of pressure, with or without the addition of heat.

The press described and claimed in the present application is an improvement on that type of press in which there is employed a curb cylinder that is provided with a tamping or pre-pressing ring at one end and a principal ram at the opposite end, the tamping ring acting to fully charge the curb and the principal ram moving in a direction opposite to that of the tamping ring to effect the extracting operation, this arrangement resulting in certain economies in the overall length of the press owing to the necessity for moving the principal ram only a short distance. The ram also includes a steam chamber that is located centrally of, and extends substantially the length, of the curb, for the purpose of heating and maintaining the charge in the curb at a temperature that will facilitate the extraction of the oils therefrom.

It is one of the objects of the present invention to provide a sealing or packing ring that is positioned at the bottom of the curb during the compressing operation effected by the principal ram in order to prevent the flow of any portion of the extracted oil inwardly and downwardly of the curb below the principal ram, and to direct this flow into the oil-collecting pan that surrounds the exterior of the curb.

A further object is to arrange principal ram for the carriage of the sealing ring at all times except during the compressing operation, special means being provided for the automatic detachment of the ring from the ram during its upward movement to squeeze the charge in the curb and to maintain the ring in its detached position adjacent the bottom of the curb, the ram again picking up the ring when moved downwardly to permit the discharge of the compressed cake.

A further object is to provide an arrangement for intermittently introducing an exhausting steam into and from the steam chamber of the ram by causing suitable ports in the ram to register with steam and exhaust pipes while the ram is occupying its lowermost or cake-discharging position, thus effectively eliminating any necessity for flexible steam hose which would otherwise move with the ram, would unnecessar-

ily clutter the press and which would interfere with the sealing ring noted above.

These and further objects of my invention will be set forth in the following specification, reference being had to the accompanying drawings, 5 and the novel means by which said objects are effectuated will be definitely pointed out in the claims.

In the drawings:

Fig. 1 is an elevation, partly in section, of 10 my improved press, the several parts being shown in curb-charging position.

Fig. 2 is a plan view of the press, as viewed in the direction of the arrow 2 in Fig. 1, showing the upper header of the press and the location of 15 the hydraulic cylinders forming part of the mechanism for actuating the tamping ring.

Fig. 3 is an enlarged section taken along the line 3—3 in Fig. 2, looking in the direction of the arrows, showing the curb in cake or residue-dis- 20 charging position, with its steam duct registering with the steam supply pipe for supplying steam to the heating chamber of the ram, and also the plungers for carrying the sealing ring on the ram, and for retaining this ring in position adjacent 25 the bottom of the curb.

Fig. 4 is a section of a portion of the machine, corresponding to that shown in Fig. 3, but illustrating the principal ram in a position wherein it is beginning to compress the charge in the curb 30 and with the sealing ring about to be disengaged therefrom.

Fig. 5 shows a step in the operation of the press, subsequent to that illustrated in Fig. 4, the ram having moved further upward and the 35 sealing ring having been completely disengaged.

Fig. 6 is a section along the line 6—6 in Fig. 3, looking in the direction of the arrows, showing the arrangement of the spring-operated plungers which support the sealing ring during the 40 compressing operation by the principal ram.

Fig. 7 is an elevation of one end of the plunger shown in Fig. 6, looking in the direction of the arrow 7.

Fig. 8 is a section along the line 8—8 in Fig. 45 3, looking in the direction of the arrows, showing the arrangement of the spring pressed plungers which serve to support the sealing ring on the ram.

The specific embodiment of my invention, as 50 set forth in the present application, relates to a press for the extraction of greases from animal tissues or cracklings. Only a single type of press is disclosed, i. e., vertical, but it will be understood that a feature, such as the steam feed to 55

the heating chamber forming a part of the ram, is likewise capable of use in connection with a horizontal type of press. Moreover, it will be understood that, notwithstanding the specific disclosure of my invention takes the form of a press for the extraction of oils and greases, the broader phases of the invention are likewise applicable to the general extraction of fluids from any material that may be subjected to pressure for this purpose.

Referring to Fig. 1 of the drawings, the numeral 10 designates a suitable foundation which is provided with a pocket 11. Disposed above the bottom of the pocket on opposite sides thereof is a pair of girders 12, upon each of which rests a pair of nuts 13 that are mounted upon the lower ends of a pair of tie rods 14 that extend upwardly through the adjacent end of a lower header 15. In plan view, the header 15 possesses a generally rectangular conformation, as shown in Fig. 2 which illustrates the upper header 16. A tie rod 14 is located adjacent each corner of the lower header 15 and these rods project upwardly through the upper header 16 to receive on their upper extremities nuts 17, similar to the nuts 13. Each of the headers is maintained in abutting relation to its corresponding nuts 13 and 17 by means of clamping collars 18. The headers and tie rods constitute a box-like structure which forms the principal framing of the press and the entire weight of which is carried on the girders 12.

Preferably integrally formed with the header 15 is a hydraulic cylinder 19 that extends downwardly into the pocket 11 and has reciprocably mounted therein a piston 20. Actuating fluid, such as oil and the like, is introduced into the cylinder 19 by means of a pipe 21 that is in communication with a remote pumping mechanism.

An annular shell 22 projects upwardly above the head 23 of the piston and has seated on the upper end thereof a ram 24. A sleeve-like portion 25 depends from the underside of the ram and is guidably received within the interior of the shell 22 so that when fluid is introduced into the cylinder 19, the piston 20 and the ram 24 will move as a unit. Owing to the fact that the shell 22 is to all intents and purposes an integral part of the ram, this shell will hereinafter be referred to, for convenience, as the ram apron.

A hollow stem 26 projects upwardly from the ram 24 in axial alignment with the cylinder 19 and encloses a steam space or chamber 27 into which steam is delivered and exhausted by means of pipes 29 and 30, respectively, which project upwardly through a disc 28 that closes the lower end of the chamber (see Figs. 1 and 3). The upper end of the inlet pipe 29 terminates at some distance above the disc 28, while the upper end of the exhaust pipe is substantially flush with the inner surface of said disc in order that it may conveniently drain away any water of condensation that may collect in the steam chamber. The pipes 29 and 30 communicate with other pipes which may be located in convenient locations around the ram, but which are of identical construction. For the details of construction, therefore, reference will hereinafter be made only to the system of piping which communicates with the inlet pipe 29.

Referring to Fig. 3, the lower end of the pipe 29 is connected to a pipe 31 that extends through the ram sleeve and apron, 25 and 22, respectively, and which, for some convenient portion of its length may be insulated from the indicated ram

elements by means of an asbestos sleeve 32, the inner end of which abuts against a shoulder provided in the sleeve 25, while the outer end is in contact with, and protected against the action of the steam by a bushing 33 that is seated in the end of the hole which receives the insulating sleeve 32. The outer end of the bushing 33 is substantially flush with the surface of the apron 22 and defines a port 34 for a purpose presently explained.

The port 34 is intended to register under conditions hereinafter described with a port 35 defined by the end of a pipe 36 that is slidably supported in a ferrule 37 threaded in one end of a cap 38 that is bolted or otherwise secured to the lower header 15. A spiral spring 39 encircles the pipe 36, the outer end of the spring abutting against the ferrule 37, while the inner end contacts with an annular flange 40 formed on said pipe, thus tending to always urge the pipe toward the ram 20 apron 22. A gasket 41 is interposed between the surface of the ram apron and the flange 40 for the purpose of providing an effective seal with the apron surface, both when the ports 34 and 35 occupy the registering position shown in Fig. 3 and also when occupying the relatively displaced position, as shown in Fig. 1. It is contemplated that the outer end of the pipe 36 may be connected, either by a flexible hose to a suitable steam supply, or by some form of slip connection with an ordinary pipe that will not interfere with the extending action of the spring 39.

From the foregoing, it will be understood that when the ram is occupying the position shown in Fig. 3 fresh steam will be supplied to the steam chamber through the pipe 29, while the condensate and other steam will be exhausted through the pipe 30 that is in communication with a piping system substantially identical with the pipes 31 and 36, and the allied parts. However, when the ram has moved upwardly to the position shown in Figs. 1, 4, and 5, the supply of steam to the steam chamber will be cut off.

Above the steam pipe 31, the ram is provided with a plurality of radially-extending plungers 42 that are mounted within appropriate chambers 43, the inner end of each plunger being slidably in a hole 44 having a diameter less than the diameter of the chamber, while the outer end is slidably mounted in a plug 45 threaded in the entrance to the chamber 43. A disk 46 is fixed on the plunger 42 and provides an abutment for one end of a coil spring 47 that encircles the plunger, the opposite end of the spring abutting against the shoulder defined by the junction of the chamber 43 and the hole 44. The tendency of the spring 47 is to always urge the plunger radially outward of the ram and the outer end of the plunger is rounded as at 48 for reception within an annular groove 49 provided in a sealing ring 50 whose working face may be channeled or otherwise recessed to receive suitable packing 51. In the position of the ram shown in Fig. 3, the sealing ring 50 is supported by the plungers 42, with the top surface of the ring contacting with a shoulder 52 provided on the ram and the working face of the ring projecting laterally beyond the peripheral face of the ram to define a shoulder 53 for a purpose hereinafter explained. As in the case of the sealing ring, the peripheral face of the ram may also be channeled or otherwise recessed to receive a packing or gasket ring 54. The squeezing surface 55 of the ram is preferably inclined outwardly from the steam chamber, as shown in Fig. 3.

The ram 24 (Fig. 1) normally closes the lower end of a curb 56 which comprises a plurality of axially-spaced rings 57 that are internally connected by means of longitudinally-extending bars 58. These bars are arranged in the manner of barrel staves, but are spaced circumferentially from each other sufficiently to provide openings 59 that are wide enough to permit of the easy flow of oils or greases therethrough, while substantially restricting the outward movement of solid material when under pressure. Secured to the lower ends of the bars is a ring 60 whose inner surface is substantially in alignment with the inner surfaces of the bars and forms a sliding fit with the peripheral surface of the ram, so that the latter, when occupying the position shown in Fig. 1, effectually closes the lower end of the curb. The ring 60 also comprises an annular, upstanding flange 61 which defines an oil-collecting channel 62 that is in communication with a flexible hose 63 through which the collected oil or grease is evacuated. In order to maintain the oil in the channel 62 above the congealing point and so facilitating its handling, the ring 60 preferably embodies an internal, annular passage 64 which is in communication on one side of the ring with a flexible steam, inlet hose 65 and on the opposite side with a corresponding hose 66 through which the steam is exhausted from the passage.

Referring to Figs. 3 and 6, there is illustrated a plurality of plungers 67 appropriately spaced around the ring 60 for the purpose of supporting the sealing ring 50 at predetermined times in the manner presently described. Each of the plungers 67 is slidably mounted in a chamber 68 formed in the ring 60 and is provided with a head 69 that projects beyond the inner face of the ring 60. The head 69 provides a slidable support for one end of the plunger and the stem 70 thereof extends through the rear wall of the chamber 68 into a cavity 71. A screw 72 is bridged between the opposite walls of the cavity through an elongated slot 73 provided in the stem 70. A coil spring 74 encircles the shank between the head 69 and the outer wall of the chamber 68 and tends to always urge the plunger toward the right, as viewed in Fig. 3, or to a position in which the head 69 bears the relation indicated above to the inner surface of the ring 60. The lower side of the head 69 is beveled as at 75 at some convenient angle, while the upper side of the head is beveled as at 76 at a steeper angle, relative to a vertical plane passing through the head, than is the surface 75, these surfaces being provided for a purpose hereinafter explained. The relative disposition of the surfaces 75 and 76, that is, lower and upper, is maintained by reason of the coaction of the screw 72 with the slot 73 which constrains movement of the plunger 67 in endwise directions only. As clearly shown in Fig. 3, the annular, inner surface of the ring 60 is set back from the corresponding surfaces of the curb bars 58 to thereby define a shoulder 77 which is utilized, in the manner hereinafter described, to disengage the sealing ring 50 from the ram when the latter is moved upwardly to compress the charge in the curb.

In order to provide for the free movement of the curb 56 along the rods 14, arcuate shoes 78 are attached to the upper curb ring 57 and also to the lower ring 60. The curb is free to move upwardly from the position shown in Fig. 1, but movement downwardly is restricted by a plurality of clamping collars 79, one for each of the rods 14. A material supply tube 80 is slidably mounted in

the upper header 16 in axial alignment with the curb and the cylinder 19 and it is through this tube that the oil-bearing material is delivered to the curb. The lower end of the tube projects below the header 16 and has attached thereto a tamping ring 81 whose dimensions are such that it fits closely in the annular space 82 created between the curb and the stem 26.

The tamping ring is also hydraulically actuated by means of a pair of piston rods 83 located on opposite sides of the tube 80 and which project upwardly through the header 16 into a pair of cylinders 84 mounted on the upper side of the header 16. A piston 85 is mounted on the upper extremity of each piston rod and this piston is of the double-acting variety. Actuating fluid is introduced into the cylinders above the pistons through pipes 86 to thereby move the tamping ring downwardly from the position shown in Fig. 1, while the reverse movement of the ring is effected by the delivery of fluid into the cylinders below the pistons through pipes 87, it being understood that the pipes 86 and 87 are in communication with some form of pump mechanism.

A pair of segmental stops or shoulders 88 depend from the underside of the header 16 to constitute abutments for the tamping ring during the pressing operation of the ram, as hereinafter explained. A pair of oppositely extending chutes 89 are carried by the lower header 15 and are so disposed with reference to the lower end of the curb that, when the ram is moved downwardly upon the completion of the pressing operation to provide a discharge opening for the residue, the latter will fall directly on the chutes on opposite sides of the press for subsequent transfer to containers, belt conveyors, or the like.

In the operation of the press, it will be understood that, when the several parts of the press are occupying the relative positions shown in Fig. 1, the press is in condition to be charged, since the ram is closing the lower end of the curb, while the tamping ring is sufficiently elevated to provide communication between the interior of the curb and the supply tube 80 which is constantly or intermittently filled with the oil-bearing material. The material is permitted to flow into the curb by gravity until the curb has become loosely packed, whereupon the tamping ring is moved downwardly to more completely pack the initial charge and to also effect a slight degree of compression which may be sufficient to extract some oil from the material. This downward movement of the tamping ring also serves to cut off the downward supply of the material in the tube 80. It will be understood that the ram is maintained in the position shown in Fig. 1 by an appropriate pressure established in the cylinder 19, so that the ram serves as an abutment against the pressing action of the tamping ring. The tamping ring is thereupon retracted to permit an additional accumulation of loosely packed material in the curb, followed by another tamping operation to compress this portion of the charge, and these steps may be repeated as often as is desirable until the curb has been completely charged with pre-pressed, oil-bearing material, whereupon the tamping ring 81 will be retracted to the position shown in Fig. 1, that is, in abutting relation to the stop 88.

The fluid pressure in the cylinder 19 is then increased to thereby move the ram upwardly and apply the maximum compression to the charge in the curb, this compression being eventually directed against the tamping ring 81 which is held in position, and the upward movement of 75.

the stem 26 serving to automatically cut off the flow of material to the tube 80 during this phase of the operation.

During this upward movement of the ram, the sealing ring 50 is carried thereby during the initial stages of the movement through the medium of the plungers 42, as above described. The ring 51 is retained in the indicated position until after it has passed above the plungers 67, these plungers being forced inwardly against the springs 14, as permitted by the general inclination of the bevel surfaces 15. Upward movement of the ring 50, however, is stopped by contact of the ring with the annularly-disposed shoulders 11 (see Fig. 4), whereupon the continued, upward movement of the ram effects a disengagement of the ring from the supporting connection afforded by the plungers 42, and the ring is then supported upon the bevel surfaces 16 of the plungers 61. The top surface of the ring 50, in the position shown in Fig. 4, is substantially flush with the top surface of the annular flange 90 forming a part of the ring 60, so that when the ram has moved to the position shown in Fig. 5, the ring 50 will be located in a position to deflect any grease that may flow downwardly between the bars 58 outwardly into the oil channel 62 and will thereby prevent the flowing of any oil inwardly of the ring 60 onto the chute 89. Upon the completion of the principal pressing operation, the pressure in the cylinder 19 is relieved, and pressure is established in the cylinders 84, thus moving the tamping ring 81 downwardly and serving to assist the downward movement of the ram which tends to fall by gravity. This downward movement of the ram is for the purpose of effecting a discharge of the residue cake from the curb and, when the shoulder 52 of the ram again contacts with the ring 50, supporting engagement of the plungers 42 will be re-established with the ring, and the plungers 67 will be moved outwardly to permit the eventual positioning of the ram in the position shown in Fig. 3, that is, in a position where the ram is completely located below and in spaced relation to the bottom of the curb to facilitate the discharge of the residue cake onto the chutes 89 which is effected by the downward movement of the tamping ring. When the ram has reached the lowermost position shown in Fig. 3, the steam inlet ports 34 and 35 register to permit the passage of steam into the chamber 27, it being understood, as described above, that a similar pair of ports are located in some other convenient position around the ram for the purpose of effecting an exhaust of steam, or the evacuation of condensate. The registration of these ports is effected intermittently during the operation of the machine, that is, during each discharge of the compressed cake, so that the chamber 27 is kept filled with steam in order to maintain the material in the curb at the best temperature possible for the most efficient extraction of the oils and greases therefrom. Prior to the initial filling of the curb, that is, when the machine is first placed in operation after having been allowed to remain idle for a time, it will be understood that the ram will be moved to the position shown in Fig. 3 and maintained there until the steam chamber has become sufficiently heated to provide the best results.

The manner of introducing the steam into the steam chamber, while described in the present application as being adaptable for use with the

vertical type of machine, is also capable of application to the horizontal type.

I claim:

1. An hydraulic press of the vertical type comprising in combination, a curb, a ram movable into the curb to compress the charge therein, a detachable sealing ring mechanically connected to and movable with the ram for closing the bottom of the curb, means for automatically disengaging the ring from the ram during its movement to compressing position, and means for holding the ring adjacent the bottom of the curb. 10

2. An hydraulic press of the vertical type comprising in combination, a curb, a ram movable into the curb to compress the charge therein, a set of yieldable plungers carried by and extending outwardly of the ram, a sealing ring detachably carried by the ends of the plungers, means engageable with the ring to detach the same from the plungers during movement of the ram to compressing position, and means for holding the ring adjacent the bottom of the curb. 20

3. An hydraulic press of the vertical type comprising in combination, a curb, a ram movable into the curb to compress the charge therein, a set of yieldable plungers carried by and extending outwardly of the ram, a sealing ring detachably carried by the ends of the plungers, means on the curb engageable with the ring to detach the same from the plungers during movement of the ram to compressing position, and a second set of yieldable plungers mounted in the curb adjacent the bottom thereof, said last-named plungers yielding to permit movement of the ring thereby during the movement of the ram to compressing position and thereafter extending to support the ring adjacent the bottom of the curb. 30

4. An hydraulic press of the vertical type comprising in combination, a curb, a ram movable into the curb to compress the charge therein and retractable to a position below the curb to provide a discharge opening for the compressed cake, a sealing ring detachably carried by the ram, means for detaching and reattaching the ring from and to the ram during the latter's movement to compressing and cake-discharging positions, respectively, and means for supporting the ring while detached in a position adjacent the bottom of the curb. 45

5. An hydraulic press of the vertical type comprising in combination, a curb, a ram movable into the curb to compress the charge therein and retractable to a position below the curb to provide a discharge opening for the compressed cake, a sealing ring detachably carried by the ram, means for detaching the ring from the ram during the movement thereof to compressing position, means for supporting the ring adjacent the bottom of the curb, and means on the ram for disengaging the ring from its curb-sealing position during the retracting movement of the ram, said ring re-engaging with the ram prior to being released from its curb-sealing position. 60

6. An hydraulic press of the vertical type comprising in combination, a curb having a shoulder adjacent the bottom thereof, a ram provided with a shoulder movable into the curb to compress the charge therein and retractable to a position below the curb to provide a discharge opening for the compressed cake, an oil-seal ring surrounding the ram adjacent the shoulder thereof, means for detachably holding the ring on the ram, said ring being detached from the ram by engaging the curb shoulder during movement of the ram to compressing position, and yieldable means for sup- 75

porting the ring adjacent the bottom of the curb after detachment from the ram, the ram shoulder engaging the ring during the retracting movement of the ram to re-position the ring on the ram.

5 7. An hydraulic press of the vertical type comprising in combination, a curb, a ram movable into the curb to compress the charge therein, a de-

tachable sealing ring mechanically connected to and movable with the ram for closing the bottom of the curb, means for automatically disengaging the ring from the ram during its movement to compressing position, and mechanical means for holding the ring adjacent the bottom of the curb.

JOHN B. MIDDAUGH.
